UNITED STATES PATENT OFFICE

115,045

DESIGN FOR A GAME APPARATUS

Otto Lobl, Middleboro, Mass.

Application March 23, 1939, Serial No. 83,800

Term of patent 7 years

To all whom it may concern:

Be it known that I, Otto Lobl, formerly of Germany, who have declared my intention of becoming a citizen of the United States, residing in Middleboro, in the county of Plymouth and State of Massachusetts, have invented a new, original, and ornamental Design for a Game Apparatus, of which the following is a specification, reference being had to the accompanying drawing, forming part thereof.

Fig. 1 is a top perspective view of a game apparatus, showing my new design;

Fig. 2 is a sectional view taken on the line 2—2 of Fig. 1; and

Fig. 3 is a section taken on line 3—3 of Fig. 1.

I claim:

The ornamental design for a game apparatus, as shown.

OTTO LOBL.
